UNITED STATES PATENT OFFICE.

SIDNEY D. WALDON, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,144,514.

Specification of Letters Patent. Patented June 29, 1915.

Application filed November 1, 1913. Serial No. 798,694.

To all whom it may concern:

Be it known that I, SIDNEY D. WALDON, a citizen of the United States, and resident of Detroit, Wayne county, State of Michigan, have invented certain new and useful improvements in Hydrocarbon-Motors, of which the following is a specification.

This invention relates to hydrocarbon motors and particularly to the cylinder, piston and connected parts.

It is well known, in hydrocarbon motors, that on the compression and exhaust or up strokes of the piston, the latter tends, by reason of the angularity of the connecting rod and the pressure on top of the piston, to press closely against one side of the cylinder, and all of the clearance if any, between the piston and cylinder, is at the opposite side. On the intake or first down stroke there is probably little change in this respect as the piston is being pulled down by the connecting rod, unless perhaps the top of the piston may be rocked across to the opposite side by reason of the change in angularity of the connecting rod at the top of the stroke. But on the firing or second down stroke, that is, the stroke following the compression stroke, as soon as the crank pin passes dead center and the explosion occurs the side pressure on the piston is immediately transferred from one side of the cylinder to the other, and if there is looseness in the piston, that is, appreciable clearance between the piston and cylinder as when the motor is cold, what is termed a "piston slap" results. In other words, this "flopping" of the piston from one side of the cylinder directly to the other at the moment of explosion causes a sharp click which is objectionable in motors for use in motor vehicles where quietness is very desirable. This "piston slap" is usually more noticeable when the motor is cold, as when starting, and frequently disappears after the motor has warmed up due to the expansion of the piston and consequent elimination of "clearance" between the piston and cylinder.

As is well known, the piston of a hydrocarbon motor is connected to the motor crank shaft through a connecting rod which is

journaled at its big end on the crank pin and at its smaller end on the piston pin. In these connections slight play is usually allowed to permit the piston to adjust itself 55 in the cylinder endwise of the piston pin.

One of the objects of the present invention is to so construct the piston and the adjacent parts that the piston will tend to slide in closer contact with the cylinder wall along 60 the line of one end of the piston pin than along the line at the opposite end thereof.

Another object of the invention is to produce a motor in which the piston in transferring from one side of the cylinder to the 65 other, as at the beginning of the firing stroke, will do so by a sliding movement around one end of the piston pin instead of jumping directly across as heretofore.

These and other objects of the invention 70 are obtained in the motor illustrated in the drawings forming a part of this specification, and in which:

Figure 1 is a vertical longitudinal section through a motor embodying one form of 75 this invention; Fig. 2 is similar to Fig. 1 with the lower part omitted and showing another form of the invention; and Fig. 3 is another view of the motor shown in Fig. 2 illustrating the close fit of the piston and 80 cylinder in a heated condition of the motor.

Referring to the drawings, 10 represents the motor base or crank case and 11 is the crank shaft mounted in bearings 12. The crank shaft is shown as having several 85 throws and the cheeks 13 are connected by suitable crank pins as at 14.

Mounted upon the crank case and suitably connected thereto is the motor cylinder 15, which may have the usual water jacket 16 90 and other attachments and valves, not shown. The trunk piston 17 is shown in the cylinder and is provided with any desired number of piston rings 18. The piston pin 19 is secured in the piston by screw 95 20, and the connecting rod 21 is journaled at its big end 22 on the crank pin 14, and at its smaller end 23 on the piston pin as shown.

Heretofore, as suggested above, it has been customary to permit the piston to float endwise of the piston pin to adjust itself to the cylinder, but in the form of the present in-

vention shown in Fig. 1, the bushing 24 is formed with an end flange 25 which just fills the space between the end 23 of the connecting rod and the internal boss 26 of the 5 piston when the latter is in close contact with the cylinder wall in line with that end of the piston pin which is journaled in said boss 26. Thus the piston is so held throughout its reciprocation except as the pressure 10 on top of the piston, due either to compression of a charge or explosion thereof, may tend to bring the piston into still closer contact with the cylinder at 90° from said line, and when the piston moves across the cylinder 15 at the beginning of the firing stroke, instead of "flopping" directly across as in previous constructions, it slides around the wall of the cylinder and is at all times in close contact with some part of it. It will 20 be understood that there will be a slight yielding of the connecting rod to permit the piston to move slightly endwise of the piston pin as on the explosion stroke, but this is hardly appreciable due to the length of 25 the connecting rod and the small degree of movement of the piston, the latter being only a few thousandths of an inch at most. As shown in Fig. 1 the piston is in close 30 contact with the cylinder wall on the line of the right hand end of the piston pin and the clearance at the opposite side of the piston is shown at 27, greatly exaggerated of course, for clearness.

In Figs. 2 and 3, another form of the invention is shown, all the parts being the same as in Fig. 1 except that the filling flange 25 is omitted and a coil spring 28 substituted therefor. This spring 28 surrounds part of the upper end of the connecting rod and presses the boss and consequently the piston toward the right, thus yieldingly tending to maintain the piston against one side of the cylinder in the direction of the piston pin. Of course the piston 45 is subject to sliding around the cylinder wall when there is pressure on top of it, as above pointed out, but the tendency of the spring 28, and of the connecting rod 21 against the upper end of which it acts, is to press the piston yieldingly endwise of the piston pin.

It will be understood that if the fit between the piston and the cylinder is so loose, either intentionally or by reason of wear, that there is a perceptible movement of the 55 piston across the cylinder at the beginning of the firing stroke even after the motor has warmed up, the spring 28 will act constantly to prevent "piston slap" but in most cases the "slap" occurs only when the motor is 60 cold, and as soon as it is heated up, the fit is closer as shown in Fig. 3 where there is no perceptible clearance, and the spring 28 then has no work to perform. It will also be understood that the invention is not limited to the exact details shown, as it will be

apparent that changes and other modifications may be made without departing from the spirit or scope of the invention.

Having thus described my invention, what I claim and desire to secure by Letters Pat- 70 ent is:—

1. In a motor, the combination with the cylinder and piston therein, of means tending to cause that side of the piston adjacent one end of the piston pin to travel in closer 75 contact with the cylinder wall than the opposite side thereof.

2. In a motor, the combination with the cylinder and piston therein, of means tending to cause the piston to lie closer to the 80 cylinder wall along the line of one end of the piston pin.

3. In a motor, the combination with the crank case and the cylinder thereon, the crank shaft, piston and connecting rod, said 85 piston sliding in the cylinder with the side adjacent one end of the piston pin tending to closer contact with the cylinder wall than the opposite side thereof.

4. In a motor, the combination with the 90 crank case and the cylinder thereon, the crank shaft, piston, and connecting rod, of means for yieldingly pressing the piston against one side of the cylinder, longitudinally of the crank shaft.

5. In a motor, the combination with the crank case and the cylinder thereon, the crank shaft, piston and connecting rod, of means between the upper end of the connecting rod and the piston for yieldingly pressing the piston against one side of the cylinder, longitudinally of the crank shaft.

6. In a hydrocarbon motor, the combination with the crank case and the cylinder thereon, the crank shaft, piston and connecting rod, of means for yieldingly pressing the piston against one side of the cylinder in the direction of the piston pin.

7. In a hydrocarbon motor, the combination with the crank case and the cylinder thereon, the crank shaft, piston and connecting rod, of means including the connecting rod as an element for yieldingly pressing the piston against one side of the cylinder in the direction of the piston pin.

8. In a hydrocarbon motor, the combination with the cylinder, connecting rod and piston, of a spring arranged between the connecting rod and piston for pressing the piston yieldingly against one side of the 120 cylinder.

9. In a motor, the combination with the crank case and the cylinder thereon, the crank shaft, piston and connecting rod, of mechanical means for yieldingly pressing 125 the piston against one side of the cylinder in the direction of the piston pin.

10. In a hydrocarbon motor, the combination with the crank shaft, the cylinder mounted above the crank shaft, the piston 130

in the cylinder, and a connecting rod having a bearing on the crank pin of the crank shaft at one end and connected to the piston by a piston pin at the other end, of means tending yieldingly to move the piston end of the connecting rod relative to the piston in the direction of the piston pin.

In testimony whereof I affix my signature in the presence of two witnesses.

SIDNEY D. WALDON.
